WILLIAM MONELL STANBROUGH.

INVENTOR
BY HIS ATTORNEY

L. Stanbrough

UNITED STATES PATENT OFFICE.

WILLIAM M. STANBROUGH, OF NEWBURGH, NEW YORK.

DENTAL INSTRUMENT.

Application filed March 9, 1922. Serial No. 542,464.

To all whom it may concern:

Be it known that I, WILLIAM MONELL STANBROUGH, a citizen of the United States, and a resident of Newburgh, county of Orange, and State of New York, have invented certain new and useful Improvements in Dental Instruments; and I do hereby declare the following to be a full, clear, and exact description of the invention, such as will enable others skilled in the art to which it appertains to make and use the same.

My invention consists of the novel features hereinafter described, references being had to the accompanying drawings which illustrate one of the embodiments of the invention selected by me for the purpose of illustration, and my said invention is fully disclosed in the following description and claims.

The object of my invention is to provide a gauge or guide that will serve to automatically guide the cusps of artificial teeth which are to be placed in position upon a wax "bite" by the operator, to the end that a more symmetrical arrangement be secured and in a shorter period of time. It is understood that the usefulness of the above mentioned gauge or guide has to do more particularly with the construction of full dentures, upper and lower sets of artificial teeth, and that it is particularly adapted to assist in arranging artificial upper teeth destined to be upper dentures.

A further object of my invention is to provide a tooth guide to be used in conjunction with the dental articulator disclosed in my Patent No. 1343691, patented June 15th, 1920, which will facilitate the exact and accurate positioning of the teeth in any particular artificial upper denture. This positioning will be generally along a curve insuring continuous contact of the upper and lower teeth in articulation in the mouth during any mastication excursion of the mandible. My present invention is not limited to this particular form of gauge or guide and may be, either with or without variations of form, readily accommodated to any type of articulator on the market.

A further object of my invention is to provide a stand for holding in any required position an upper plate which it is desired to attach to the upper member of the articulator preparatory to the construction or

grinding in of a lower set of teeth, and the main use of my invention is to position teeth on the wax trial plates, and for this purpose I find it very useful.

A further object of my invention is to provide a means for harmonizing the curve of Spee with the condyle path in any individual case.

My invention will better be understood by a reference to the following specification which is directed to the several figures of the accompanying drawings, which form a part hereof.

Figure 1 is the side elevation of a tooth guide embodying my invention which I have used for the purpose of illustrating the invention.

Figure 2 is a plan view of the same.

Figure 3 is a view of the front end, simple plate, no uprights.

Like letters refer to like parts in the several figures.

In Figure 1 (a) shows the condyle slots placed in the upright and arranged at an angle of approximately 35 degrees to the horizontal and adapted to receive the removal section of my dental articulator, diagrammatically represented with upper plate in position (z).

(b) represents a bearing plate or distance table which engages the projecting screw of the upper jaw member of my articulator when same is used in conjunction with this artificial tooth positioning guide.

(c) shows the plate, this preferably contains various arcs of circles (x) with radii varying from 60 to 85 mm. and a median line and with concave surface; being mounted upon the stand (d) so that it is free to be manually rotated thereon.

The stand (d) is thread connected eccentrically to the base (e) which base is normally free to slide antero-posteriorly along the bed plate (f) in the guides (t). The base is preferably eccentric or off center and has a cam action which serves to move the center of the guide laterally right or left, thus giving means of adjustment laterally.

The projection (g) attached to the base (e) is used to facilitate the turning of the said cam acting base (e) to adjust the center of guide surface to coincide with the median line of the wax base plate, or upper teeth. (h) is the upright stand portion which is not shown in Figure 3 as that

figure is to show the original simple guide as covered by the claim.

The operation of my invention is as follows:—

5 In the ideal human mouth the teeth are arranged so that their occlusal surfaces are inclined from a horizontal, in a lateral direction. This inclination describes an arc of a circle. Since this arc is present on 10 similar teeth on the right and left sides of the jaw, it has been found that if these arcs be extended, they will be continuous, and are found to be arcs of the same radical circle. This curvature in the human mouth 15 is known as the lateral compensating curve, and has been found to be an exceedingly valuable attribute for proper mastication when applied to artificial dentures.

It has further been found that the radius 20 of the curve varies in the same mouth within certain limits, according to the location at which it may be measured.

A second curvature extending antero-posteriorly, frequently referred to as the curve 25 of Spee has been found to be present on the occlusal surfaces of the teeth in an ideal human mouth. This curvature too, has been found to vary in radius depending upon the location at which measured.

30 The two curvatures above described, when combined with each other, and with other radial curvatures present, comprise in effect a concave segment of a sphere which in fact, constitutes the basis of my invention.

35 In making a new lower artificial denture to use with the old upper one, it will be seen that by understanding the requirements of the case it is possible to so position the old upper set of artificial teeth that it will be 40 situated approximately correct, or if desired a face bow can be used to transfer the upper plate from the mouth of the patient to the "tooth guide" thus assuring accurate placing of the plate upon the upper bow of the articulator,—it being situated to the desires 45 of the operator the old plate can be readily attached to the upper bow of the articulator, with plaster of Paris.

50 "A base plate" of moldable materials is fitted to the maxilla. On this "base plate" is disposed a "wax bite rim" extending from condyle to condyle. The length of the bite rim is arbitrarily assigned at the posterior condyle areas. On the anterior 55 portion, front artificial teeth are set in the wax in a pleasing harmonious esthetic arrangement.

The "base plate" with artificial teeth and "bite rim" are transferred to a cast previously attached to a movable upper frame member which is now attached to my present invention at the condyle slots. Now, since anterior teeth are arranged so that their tips describe an arc of some circle, 65 the radius of this circle is sought by bring-

ing the condylar ends of the "wax bite rim" and the tips of the already arranged anterior teeth into contact with the spheroidal segmental portion of my invention—already described, and moved about until one of the 70 radial arcs scribed on the face of the spheroidal segment rather closely approximates the radial circumference described in the tips of the anterior teeth.

I now proceed to position the necessary 75 number of properly fashioned teeth according to the lateral and antero-posterior curves described by the portion of the spheroidal segment directly under the "wax bite rim" in an alignment described and required by 80 proper esthetic restoration of facial contour and consistent with certain physical laws and facts necessary to and for efficient mastication.

This will describe the main use and to 85 fully appreciate its value, it is necessary to recall that the gauge or guide is of such general shape as to approximate the curves of the upper teeth, namely, the lateral curve and the antero-posterior curve (curve of 90 Spee), which provide support to the mandible upon lateral and protrusive motion. My invention contemplates a means of adjustment, vertically, antero-posteriorly and laterally, also by tilting or tipping thus giving a range of motion sufficient to serve the purpose intended. Having a normal "overbite" we place the teeth, the two central incisors, about half way between the rim of the saucer shaped disk, and in the central or 100 deep part of the gauge or guide. As the teeth go back the laterals, canines and bicuspids and molars 1st and 2nd follow the contour of the gauge or guide. The changed conditions are evident if the gauge or guide 105 is shifted forward so that the central incisors would be approximately at the center of the gauge or guide. In the human being the inner or palatine cusps of upper molars extend to a lower plane than do the outer or buccal cusps. The gauge or guide then serves to position artificial teeth attached to a trial plate by the usual wax medium. If it be desirable to shorten the upper teeth upon 110 the left side, it can be done by moving the base (e) to the right, then soften the wax and force the teeth to a higher plane on the left side. By having the vernier scale of approved construction, (circles, straight lines, etc.) it becomes possible to arrange 115 the artificial teeth in an accurate and expeditious manner.

In the use and operation of my invention I do not mention all of the various methods of application.

What I claim and desire to secure by United States Letters Patent, is:

1. In a tooth-guide for the positioning of artificial teeth, a plate mounted on a stand and having a concave surface against which 130

surface the teeth forming an upper artificial denture are adjusted to the natural compensating curves of the mandible.

2. In an artificial tooth-guide the combination of a bed plate containing antero-posterior guides, with vertically disposed members affixed to one end thereof, said members provided with slots at an angle to the horizontal resembling the floor of the 10 glenoid fossa in the human head; a circular base adapted to slide in said bed plate guides; a stand portion eccentrically screw threaded to said base; a template having a concave surface attached to the upper part 15 of said stand portion and adapted to be turned thereon, all substantially as and for the purposes hereinbefore set forth.

3. In an artificial tooth-guide the combination of a bed plate containing antero-posterior guides, with vertically disposed members affixed to one end thereof, said members provided with slots at an angle to the horizontal resembling the floor of the glenoid fossa in the human head; a circular base 25 adapted to slide in said bed plate guides; a stand portion eccentrically screw threaded to said base; a template having a calibrated concave surface attached to the upper part 30 of said stand portion and adapted to be turned thereon, all substantially as and for the purposes hereinbefore set forth.

4. In an artificial tooth-guide the combination of a bed containing antero-posterior guides, with vertically disposed members 35 affixed to one end thereof, said members provided with slots at an angle to the horizontal resembling the floor or the glenoid fossa in the human head; a circular base adapted to slide in said bed plate guides; a stand portion 40 eccentrically screw threaded to said base; an integral projection horizontally disposed from said base used as a means of adjustment; a template having a concave surface attached to the upper part of said stand

portion and adapted to be turned thereon, 45 all substantially as and for the purposes hereinbefore set forth.

5. In an artificial tooth-guide the combination of a bed plate containing antero-posterior guides, with vertically disposed members affixed to one end thereof, said members provided with slots at an angle to the horizontal resembling the floor of the glenoid fossa in the human head; a distance table 50 centrally disposed with said members and between said slots adapted to engage the projecting screw of the upper jaw member of dental articulators; a circular base adapted to slide in said bed plate guides; a stand portion eccentrically screw threaded to said 55 base; a template having a concave surface attached to the upper part of said stand portion and adapted to be turned thereon, all substantially as and for the purposes hereinbefore set forth. 60

6. In an artificial tooth-guide the combination of a bed plate containing antero-posterior guides with vertically disposed members affixed to one end thereof, said members provided with slots at an angle to the horizontal 65 resembling the floor of the glenoid fossa in the human head; a circular base adapted to slide in said bed plate guides; a stand portion eccentrically screw threaded to said base; an integral projection horizontally 70 disposed from said base; a distance table centrally disposed with said members and between said slots adapted to engage the projecting screw of the upper jaw member of dental articulators; a template having a 75 concave surface attached to the upper part of said stand portion and adapted to be turned thereon, all substantially as and for the purposes hereinbefore set forth.

In testimony whereof, I have signed my 80 name to this specification this 4 day of March, 1922.

WM. M. STANBROUGH.
